UNITED STATES PATENT OFFICE.

FRANK B. DAVIS, OF JOHNSTOWN, PENNSYLVANIA.

VACUUM CASTING DEVICE FOR GOLD-INLAY WORK AND THE LIKE.

1,219,710.

Specification of Letters Patent. Patented Mar. 20, 1917.

Application filed January 28, 1916. Serial No. 74,770.

To all whom it may concern:

Be it known that I, FRANK B. DAVIS, a citizen of the United States, residing at Johnstown, Cambria county, Pennsylvania, have invented a new and useful Vacuum Casting Device for Gold-Inlay Work and the like, of which the following is a full, clear, and exact description, reference being had to the accompanying drawings, forming part of this specification, in which:

Figure 1 is a view, partly in vertical section and partly in elevation, of a device embodying my invention.

Fig. 2 is a plan view of the same, partly broken away, and

Fig. 3 is a sectional view, also partly broken away, and showing a modification.

My invention relates to vacuum casting devices for gold inlay work and the like, or any casting where sharp thin edges are required; and is designed to provide a cheap and simple device of this character especially adapted for use by dentists or jewelers.

The nature of my invention will be best understood by reference to the accompanying drawings, in which I have shown a preferred embodiment thereof and which will now be described, it being premised that various changes can be made in the details of construction and arrangement of the parts without departing from the spirit and scope of my invention as defined in the claims.

Referring first to Figs. 1 and 2, the numeral 2 designates a hollow bowl of clay or other refractory material having the projecting stem 3, the whole being somewhat similar to an ordinary clay pipe. The stem 3 has an interior passage 4 which communicates with the interior of the bottom portion of the bowl by one or more openings 5.

6 designates a blower of any suitable or usual character having an outlet connection 7, to which is connected the usual flexible pipe 8 leading to the blow pipe 9. 10 designates the air inlet connection for the blower; and 11 is a piece of pipe which is adapted to be attached to the inlet 10, and to be connected to the stem 3 by means of a detachable coupling 12, which is preferably flexible. The pipe 10 is provided with an opening 13 which may be controlled by any suitable valve, such as the rotary sleeve valve indicated at 14.

The operation is as follows: While melting the material for the casting in the bowl 2, the valve 14 is moved to open the air open-

ing 13, so that there will be no suction through the stem 3. When it is desired to use suction to draw the molten metal down into the mold cavity and upon the investment, the valve 14 is moved to close the opening 3.

The dentist or other workman may be provided with a number of other different bowls 2 of different sizes adapted for different particular kinds of work, and any one of these can be quickly and readily attached to the blower by means of the coupling 12. In the modification shown in Fig. 3, the pipe 11 is omitted and the stem 3^a of the bowl 2^a is connected directly by the coupling 12^a to the inlet pipe 15 of the blower 6^a. This inlet pipe is provided with an escape opening similar to that shown in Fig. 1, and controlled by the valve 16. In this form I have also shown the bowl 2^a as provided with the bottom projections 17 which somewhat elevate the bowl from the support 18.

My invention provides an appliance of 80 the character described which can be supplied at a very small cost, and which can be conveniently used in connection with the ordinary blowers employed in blow-pipe work.

By the use of clay or similar refractory 85 material for the bowl and its stem, I prevent any oxidizing action of the bowl. A bowl of this character has practically no expansion or contraction while heating and cooling. This is a serious objection to metal cups, 90 since they expand and draw away from the investment, leaving a space between the investment and the wall of the cup, causing a leak for the air. Metal cups are also objectionable in that the investment sometimes 95 adheres to the wall of the cups and forms fissures. Clay being a poor conductor of heat, the stem may be made sufficiently long, so that there will be no danger of burning the flexible connection with the suction-producing device.

I claim:

1. A device of the character described comprising a one-piece bowl of refractory material having an integral hollow stem 105 communicating therewith, and means for connecting said stem to the intake of a blower, substantially as described.

2. An appliance of the character described comprising an integral small portable bowl of refractory material and having a projecting hollow stem communicating

with the interior of the bowl, a blower having an intake provided with an opening, a valve for controlling said opening, and a detachable coupling for coupling said stem 5 to the blower intake, substantially as described.

3. A device of the character described, comprising a bowl of refractory non-oxidizable material substantially free from expansion and contraction and having a relatively long projecting hollow integral stem communicating with its lower portion and adapted at its free end for connection to a suction-producing device, substantially as 10 described.

4. A device of the character described, comprising a one-piece bowl of refractory 15

material having an integral hollow stem communicating therewith, the bowl being arranged to receive the investment material, while the stem is of sufficient length to prevent the end thereof becoming heated, a blower having an intake provided with an opening, a valve for controlling said opening, and a detachable flexible coupling for 20 coupling said stem to the blower intake; substantially as described.

In testimony whereof, I have hereunto set my hand.

FRANK B. DAVIS.
